UNITED STATES PATENT OFFICE.

ALEXANDER T. GARDEN, OF AUGUSTA, KANSAS.

OIL REGULATOR.

Application filed August 29, 1921. Serial No. 496,711.

To all whom it may concern:

Be it known that I, ALEXANDER T. GARDEN, a citizen of the United States, residing at Augusta, in the county of Butler and State of Kansas, have invented a new and useful Oil Regulator, of which the following is a specification.

This invention relates to an oil regulator primarily designed to be coupled to a dia-
phragm steam regulator whereby a con-
siderable saving of fuel can be effected by
the automatic control of the supply of oil.

Another object is to provide a regulator
of this character which is simple, durable
and compact in construction, formed of few
parts, will not easily get out of order, and
can be cleaned and repaired easily.

With the foregoing and other objects in
view which will appear as the description
proceeds, the invention resides in the com-
bination and arrangement of parts and in
the details of construction hereinafter de-
scribed and claimed, it being understood
that, within the scope of what is claimed,
changes in the precise embodiment of the
invention shown can be made without de-
parting from the spirit of the invention.

In the accompanying drawings the pre-
ferred form of the invention has been shown.

30 In said drawings

Figure 1 is a view partly in elevation and
partly in section of the device.

Figure 2 is an enlarged section on line
2—2, Figure 1.

35 Referring to the figures by characters of
reference 1 designates the body of the regu-
lator, the same being provided at its ends
with ears 2 whereby it can be attached
readily to a supporting structure. Extend-
ing longitudinally within this body are par-
allel bores 3 and 4 respectively each having
its lower end counterbored as shown at 5
and 6 respectively. Screwed into the coun-
terbore 5 is a reducer plug 7 having a head
45 8 provided with a threaded recess 9 therein
communicating with an oil passage 10. A
plug 11 is similarly mounted within the
counterbore 6 and has a steam passage
therethrough. The upper ends of the bores
50 3 and 4 are closed by screw plugs 12.

An opening 13 is provided in the wall of
the body and communicates with the bore
4 and another opening indicated at 14 com-
municates with the bore 3.

55 Formed in the body 1 near its upper end
and at diametrically opposed points are

openings 15 in which are seated suitably
packed bearings 16 for oppositely extending
shafts 17. Each shaft is provided at its
inner end with a head 18 from which ex-
tends a radial actuating finger 19 prefer-
ably rounded. One of the fingers 19 is ar-
ranged diametrically within the bore 3
while the other finger is arranged diametri-
cally within the bore 4. A plunger valve
20 is mounted for reciprocation in the bore
3 and has a diametrical slot 21 into which the
finger 19 extends. Another plunger valve
22 is slidable in the bore 4 and is likewise
slotted to receive the other finger 19.

Arms 23 are connected to the outer ends
of the shafts 17 and are adapted to be cou-
pled to a steam regulator so that when the
shafts 17 are rotated the flow of oil be-
tween the opening 14 and passage 10 and
the flow of steam between the opening 13
and the passage within the plug 11 will be
increased or reduced according to the di-
rection of movement of the plungers 20
and 22 by the fingers 19. The plugs 7 and 11
constitute seats for the plunger valves
20 and 22.

Obviously by connecting a regulator such
as described to any portable or stationary
boiler a great saving of fuel will be ef-
fected because the fuel will only be con-
sumed as required to maintain pressure.

What is claimed is:—

1. A regulator of the class described in-
cluding a body having longitudinal bores
extending therethrough, ports opening into
the respective bores, plugs closing the bores
at one end, plugs seated in the other end
of the bores and having passages there-
through and also constituting valve seats,
plungers mounted to slide within the re-
spective bores and constituting valves, rock
shafts journaled within the body, and means
extending from the shafts for engagement
with the respective plungers to actuate
them when the shafts are rotated.

2. A regulator of the class described in-
cluding a body having parallel bores, there
being ports opening into the respective
bores, combined plugs and valve seats clos-
ing the bores at one end and having open-
ings therethrough, plugs closing the other
ends of the bores, plungers within the re-
spective bores and constituting valves, op-
positely extending shafts, means for rotat-
ing them, and cooperating means upon the
shafts and the respective plungers for

transmitting motion from the shafts to the plungers.

3. A regulator of the class described including a body having bores extending therethrough, each bore being provided with a port, plugs detachably mounted in the bores at one end and constituting valve seats, there being openings through the plugs, plungers mounted to reciprocate within the respective bores and constituting valves, shafts journaled in the body, sep-

arate means for rotating the respective shafts, and means operated by said shafts for reciprocating the respective plungers.

In testimony whereof that I claim the foregoing as my own, I have hereto affixed my signature in the presence of two witnesses.

ALEXANDER T. GARDEN.
